Primary Examiner—Antoine D. Davis*Assistant Examiner*—Patricia Palasik(74) *Attorney, Agent, or Firm*—Harness, Dickey & Pierce, P.L.C.(57) **CLAIM**

The ornamental design for a container sensor, as shown and described.

DESCRIPTION

FIG. 1 is a perspective view of a container sensor in accordance with the present invention;

FIG. 2 is a front plan view of the container sensor of FIG. 1;

FIG. 3 is a left side plan view of the container sensor of FIG. 1;

FIG. 4 is a top plan view of the container sensor of FIG. 1;

FIG. 5 is a rear plan view of the container sensor of FIG. 1;

FIG. 6 is a bottom plan view of the container sensor of FIG. 1; and,

FIG. 7 is a right side plan view of the container sensor of FIG. 1.
